United States Patent Office

Des. 181,551
Patented Nov. 26, 1957

181,551

DRAFTSMAN'S TEMPLATE

Harold Sellman, San Francisco, Calif.

Application July 30, 1956, Serial No. 42,438

Term of patent 14 years

(Cl. D52—1)

FIG. 1

I claim:

The ornamental design for a draftsman's template, as shown.
